UNITED STATES PATENT OFFICE.

FRANCIS LEMOINE, OF MONTREAL, QUEBEC, CANADA.

EXCAVATOR.

1,235,704.

Specification of Letters Patent. Patented Aug. 7, 1917.

Application filed November 26, 1915. Serial No. 63,645.

To all whom it may concern:

Be it known that I, FRANCIS LEMOINE, a subject of the King of Great Britain, and residing in the city of Montreal, in the Province of Quebec, in the Dominion of Canada, have invented certain new and useful Improvements in Excavators; and I do hereby declare that the following is a full, clear, and exact description of the same.

10 The invention to be hereinafter described relates to "excavating machines".

One object of the invention is to provide a simple, efficient, compact and economical construction permitting the body of the machine to be swung considerably out of line or to one side of the derrick beam.

Another object is to provide a machine that may rest continually on solid ground when digging trenches or other excavations, thus eliminating bracing of trenches, scaffolding to support the machine. A further object is to provide simple, efficient and compact devices for guiding the bucket lifting cables, where they pass through the upper part of the derrick beam.

25 In order to more clearly disclose the construction, operation and use of the invention, reference should be had to the accompanying drawings forming part of the present application. Throughout the several figures of the drawings, like reference characters designate the same parts:

In the drawings, Figure 1 is a side elevation;

35 Fig. 2 is a front view;

Fig. 3 is a view similar to Fig. 1, the dotted lines indicating the bucket beam as stowed away.

Fig. 4 is a top plan view of the invention;

40 Fig. 5 is a top plan view of the lower set;

Fig. 6 is a side elevation of Fig. 5.

Fig. 7 is a top plan view of the upper set of rope guides; and Fig. 8 is a side elevation of Fig. 7.

45 With reference to the drawings; 1^a is the body of the machine; 2^a are the hoisting winches; 3^a is the supporting truck; 4^a is the turn table suitably mounted on a turning gear; 5^a is a derrick beam and 6^a is a bucket beam; 7^a is a mechanism for driving the bucket beam gear and pinion.

To the lower end of the derrick beam is securely fixed a ball head 1 adapted to be universally seated in a coöperating cup shaped socket 2 formed in a plate 3 which is made fast to the forward part of the ma-

chine body. The socket is provided with two diametrically opposite perforations 4 and the head is provided with a plurality of bores 5 extending diametrically through it, 60 at different angles. A suitable locking pin 6 passed through the perforations 4 and one of the bores alined therewith, will securely lock the derrick beam so that it will have only a vertical swing about the pin as an 65 axis or pivot. On the other hand, the ball and socket or universal coupling 1 and 2 permit the body of the machine to swing clear to one side of the beam at any time desired. The pin may then be slipped in 70 and the beam is locked, as described.

To the lower end of the lifting derrick is also secured an angle plate 7. Between this and a shoulder 8 of the bracket 9 which carries the ball 1 are journaled a pair of 75 grooved guide rockers 10 between which is passed the draft cable 11 for performing the digging operation. Thus, when the body of the machine is swung to one side or the other, one or the other of the guide rollers 80 will engage the draft cable and guide it toward the winch without binding.

In the present machine the excavating is done with a draw cut, upwardly toward the machine, instead of the usual downward and 85 outward thrust or push.

The result is maximum digging power with minimum effort. This is accomplished by securing one end of the cable 11 to the bucket, passing it up through the lower end 90 of the derrick beam and between the guide pulleys 10 and thence on to its connection with the winding drum of its winch. The draft cable, of course, accomplishes all of the digging action with the aid of the bucket 95 beam. The pinion for raising and lowering the bucket beam is operated in the usual way, but, in the digging operation simply lifts or lowers the bucket beam gradually 100 according to need as the bucket is drawn in by the draft cable. The minimum force is required, of course, to actuate the bucket beam, in this arrangement.

One important feature of the invention is that the stability of the machine is always 105 assured as the machine travels on the even surface of the roadway and leaves the excavation after it instead of, as at present, following up the excavation and traveling on scaffolding or on the uneven bed thereof. 110

To the top of the excavation bucket is secured a lifting cable 12, to assist in lifting

the loaded bucket as well as to add to the upward pull during the excavating operation if desired. This cable is passed over an obliquely mounted vertical guide roller 13, thence over an obliquely mounted horizontal guide roller 14, and thence through a guide slot in the journal upright of the vehicle body and finally connected to its winch.

This arrangement keeps the cable away from the bucket beam and prevents all possibility of twisting or entangling.

As shown in dotted lines in Figs. 2 and 4, the body of the machine may be swung to a considerable angle to either side without in the least hindering the work of excavation.

A most important advantage of this improved excavator lies in the fact that it will be possible to dig alongside of a building, a conduit, a sidewalk, without the possibility of causing damages thereto, while with the excavators now in use, it is impossible to dig alongside of a sidewalk and usually in such cases, the work has to be done by hand.

As before stated, another important point is that the machine by drawing the bucket toward the truck will permit the operator to keep the machine on unexcavated ground, while with the machines now in use, scaffolding have to be built to support the machine over the trench as the machine follows up the excavation.

It is thought that the construction, operation, and use of the invention will be clear from the preceding detailed description.

Changes may be made in the construction,

arrangement and disposition of the several parts of the invention without in any way departing from the field and scope of the same and it is meant to include all such in this application wherein only a preferred form has been disclosed.

What I claim is:—

1. In an excavator, the combination of a truck, a frame mounted on the truck and adapted to be adjusted about a vertical axis, a socket member on the frame, a derrick beam having its inner end mounted in said socket, adjustable means connecting the base and socket whereby the beam may be maintained parallel with the length of the truck in either of several adjusted positions of the frame, a digging bucket carried by the beam, and means for moving the bucket relative to the frame.

2. In combination with an excavator, a socket adapted to be secured to the forward part of the frame thereof, and provided with pivot pin holes, a derrick beam, a head secured to said derrick beam and coöperating with said socket and provided with a plurality of bores adapted to be alined with the holes of the socket and a pivot pin adapted to be passed through said holes and bores selectively.

Signed at Montreal, Quebec, Canada, this 8th day of October, 1915.

FRANCIS LEMOINE.
